UNITED STATES PATENT OFFICE.

WILLIAM JANUS, OF ST. LOUIS COUNTY, MISSOURI, ASSIGNOR TO CHICAGO RAILWAY EQUIPMENT COMPANY, OF CHICAGO, ILLINOIS, A CORPORATION OF ILLINOIS.

ADJUSTABLE ECCENTRIC CHAIR FOR BRAKE BEAMS.

Application filed May 19, 1925. Serial No. 31,386.

This invention relates to new and useful improvements in supplemental supports for brake beams, the objects of the invention being to provide a chair adapted to be attached to a brake beam part and easily adjustable to vary in a vertical plane the points of engagement of said chair with the parts with which said chair is associated.

Further objects of the invention are to provide an eccentric member adapted to be mounted on a brake beam part and to provide simple means for adjustably attaching said member in position.

With these and other objects in view, my invention consists in certain novel features of construction and arrangement of parts, hereinafter more fully described and claimed, and illustrated in the accompanying drawings, in which—

Figure 1 is a cross sectional view taken transversely of the brake beam and showing the chair attached to a part thereof and slidably resting on a support bar.

Figure 2 is an enlarged view of the chair member.

Figure 3 is a view taken at right angles to Figure 2.

Figure 4 is a top plan view.

Figure 5 is a modified form showing the eccentric member mounted directly on the tension member.

Figure 6 is another modified form showing modified means for adjustably attaching the eccentric member in position.

Figure 7 shows the eccentric member applied to the brake beam strut.

Figure 8 is an end elevational view of a clamping member and showing modified means for securing the eccentric member in position.

Figure 9 is an elevational view of the clamping member with the eccentric member attached thereto.

Figure 10 is an elevational view of the eccentric member.

Figure 11 is a modified form of the eccentric member showing modified means for adjustably supporting the same in position.

Figure 12 is a vertical cross section taken on line 12—12 of Figure 11.

Figure 13 is a side elevational view of a strut partly broken away and showing modified means for adjustably attaching the eccentric member thereto.

Figure 14 is an end elevational view of the strut member with the eccentric member attached thereto.

Figure 15 is a fragmental view of a strut member and showing modified means for attaching the eccentric chair in position thereon.

Figure 16 is a vertical cross section taken on line 16—16 of Figure 15.

Figure 17 is an elevational view of an eccentric member provided with an anti-friction member.

Figure 18 is an enlarged detail view taken on line 18—18 of Figure 17.

Referring by numerals to the accompanying drawings, 10 indicates a part of a truck, such as a spring plank, to which is attached a support bar 11 which extends beneath a brake beam comprising a compression member 12 and a tension member 14. Clamp member 15 having a seat 16 for receiving tension member 14 is secured thereon by a suitable fastening device 17 which engages the upwardly presented spaced ends 15^a of clamp member 15 and clamps the latter in position.

Depending from clamp member 15 is a pair of downward extensions 18 provided with aligned apertures for receiving a pin 19. This pin passes through the aperture 20 eccentrically disposed in a disk 21, which latter is arranged between the legs 18 and rests on support bar 11, thereby supporting the brake beam. Disk 21 is provided with a series of apertures 22 which are disposed concentrically with respect to aperture 20 and are adapted to receive a cotter pin 24 which is adapted to be seated in apertures or seats 24^a formed in extensions 18 at points coinciding with the apertures 22.

To adjust the eccentric member 21, cotter pin 24 is withdrawn from legs 18 and eccentric member 21 is moved with the pin 19 as the axis, thereby increasing or decreasing the distance between the brake beam part 14 and the support 11. When eccentric member 21 occupies the desired position, cotter pin 24 is reinserted in the extensions 18,

passing through one of the apertures 22. In this manner, the eccentric member can be readily adjusted and when so adjusted occupies a fixed position and cannot become displaced.

Depending portions 18 of clamp member 15 are preferably angularly disposed to said

clamp member in order to permit the position of the eccentric member 21 in alignment with the support bar 11.

In the form shown in Figure 5, an eccentric member 25 is mounted directly on the tension member 14 and is held in adjusted position thereon by a screw 26 which is screw-seated in a collar 27 formed integral with said eccentric member and engages tension member 14, thereby fixing said eccentric member in its adjusted position in tension member 14.

In Figure 6 an eccentric member 28 is held in position on the tension member by means of a cotter pin 29 which passes through a diametrically disposed bore in the tension member and through a pair of diametrically aligned apertures 30 formed in collar 28^a of eccentric member 28. There is a series of apertures 30 arranged in collar 28^a wherein eccentric member 28 can be angularly adjusted relative to tension member 14. The peripheral face of member 28 carries a suitable cage 31 provided with ball bearings 32 which form an anti-friction bearing for said eccentric member.

In Figure 7, a brake beam strut member 13 is provided with a nose portion 13^a in which is mounted by means of a pin 34 an eccentric chair 35. A cotter pin 36 is seated in the bifurcated terminals of nose portions 13^a and engages one of the series of apertures 37 which are concentrically disposed about pin 34.

In Figures 8 and 9, a clamp member 38 is provided in its depending portions 39 with inwardly presented serrated faces 40 which are adapted to form interlocking engagement with serrated faces 41 eccentrically disposed on chair member 42. A bolt 44 passes through apertures 39^a formed in portions 39 and aperture 42^a eccentrically formed in member 42 and serves to draw the cooperating serrated faces together, thereby locking eccentric member 42 against accidental displacement. When it is desired to adjust member 42, the nuts on bolt 44 are loosened sufficiently to permit portions 39 to spring outwardly when member 42 is moved about the axis of pin 44. The serrations permit more accurate adjustment of the eccentric member and serve to hold the latter securely in adjusted position. Portions 39 are preferably disposed angularly relative to clamp member 38 in order to permit eccentric member 42 to be in alignment with the support bar 11.

In Figures 11 and 12 an eccentric member 45 is provided with a seat 46 which is serrated transversely and is adapted to engage serrated portion 14^b of tension member 14^a. Seat 46 is preferably formed circular to facilitate the attaching of member 45 in position and a complementary member 47 having a semi-circular serrated seat is attached

at one end to eccentric member 45 by a fastening device 48 and has its opposite end 47^a adapted to be clamped to extension 46^a by a bolt and nut device 49. By loosening device 49, member 45 can be adjusted about the axis of the tension member 14^a so as to regulate the distance between said tension member and the support member.

In Figures 13 and 14 a strut member 13^b has its bifurcated nose portions 13^c provided with inwardly disposed serrated faces 50 which are adapted to engage serrated faces 51 formed on an eccentric member 52. A bolt and nut fastening device 54 is used to draw the bifurcated portions 13^c inwardly to secure the serrated faces in interlocking engagement with each other.

In Figures 15 and 16 a bolt or pin 55 is non-rotatably seated in the bifurcated extensions of the strut member and is held against withdrawal by a cotter pin 56. The peripheral face of the intermediate portion of said pin is formed with longitudinally disposed serrations 57 which are adapted to be engaged by the serrated face 58 formed in a split collar 59 of an eccentric member 60. This split collar is adapted to be drawn together and interlock the serrated portions by means of a fastening device 61.

In Figures 17 and 18 an eccentric member 62 is shown provided with annular groove 64 in which is loosely disposed a resilient split ring 65 which loosely operates on said eccentric member and forms an anti-friction bearing surface for engaging the support bar 11. The ring is placed in position by spreading the ends thereof to enable it to pass over the annular shoulders formed by groove 64 and the inner periphery of said ring is slightly larger than the periphery of groove 64, thereby permitting said ring to be loosely mounted on the eccentric member.

I claim:

1. An eccentric support chair adapted to be mounted on a brake beam part, and adjustable eccentrically to vary in a vertical plane the points of engagement of said eccentric member with the parts with which it is associated.

2. A support chair adapted to be eccentrically and rotatably mounted on a brake beam part for varying in a vertical plane the distance between the operative points of said chair.

3. A support chair adapted to be eccentrically and rotatably mounted relative to a brake beam part for adjusting in a vertical plane the distance between the points of said chair and the cooperating elements, and means for fixedly locking said chair in adjusted position.

4. A support chair adapted to be eccentrically and rotatably mounted relative to a brake beam part for adjusting in a vertical plane the distance between the points of said

- chair and the cooperating elements, and means engaging said eccentric chair and adapted to engage said brake beam part for fixing said chair in adjusted position. 55
5. A supplemental support member for brake beams adapted to be carried by a brake beam part and eccentrically and fixedly adjustable relative to said part for varying in vertical plane the distance between said brake beam part and the supporting point of said support member. 60
6. A supplemental support member for brake beams comprising a clamp member adapted to be attached to a brake beam part, and a support member eccentrically carried by said clamp member and fixedly adjustable in a vertical plane for adjusting the distance between the operating points of said supplemental support. 65
- 10 7. A supplemental support member for brake beams comprising a clamp member adapted to be attached to a brake beam part, a support member eccentrically carried by said clamp member and fixedly adjustable in a vertical plane for adjusting the distance between the operating points of said supplemental support, and means for locking said eccentric member in adjusted position. 70
- 15 8. A supplemental support member for brake beams comprising two elements, one of which is adapted to be permanently fixed to a brake beam part and the other adapted to be eccentrically mounted on the first element and fixedly adjustable relative thereto. 75
- 20 9. A supplemental support member for brake beams comprising two elements, one of which is adapted to be permanently fixed to a brake beam part and the other adapted to be eccentrically mounted on the first element and fixedly adjustable relative thereto, and means for interlocking said elements and fixing said eccentric element in its adjusted position. 80
- 25 10. A supplemental support member for brake beams adapted to be adjustably and eccentrically mounted on a brake beam part and provided with a serrated face adapted to engage a complementary stationary serrated face for locking said eccentric member in position. 85
- 30 11. A supplemental support member for brake beams adapted to be adjustably and eccentrically mounted on a brake beam part, 90
